UNITED STATES PATENT OFFICE

2,311,916

FUEL PUMP

Gunnar A. Wahlmark, Rockford, Ill.

Application June 24, 1939, Serial No. 281,627

2 Claims. (Cl. 103—223)

More particularly, the invention relates to fuel pumps of the type used with domestic oil burners, and to a means for preventing hum during operation of the pumping mechanism.

In an oil burner installation, an objectionable hum is sometimes encountered. Many attempts have been made to eliminate this noise, but invariably the means provided functions in such a manner that the noise recurs as the fuel tank empties or after the oil burner has been started a number of times. It is the general object of this invention to provide a new and improved fuel pump having means for eliminating such noise.

A further object is to provide a fuel pump having a casing provided with a removable closure and an anti-hum device associated therewith.

Another object is to provide a fuel pump with a closed air chamber associated with the fuel on the intake side of the pumping mechanism, said air chamber being provided with one wall formed of an impregnated cloth, generally referred to as "airplane" cloth, this cloth diaphragm serving to seal a quantity of air within said chamber.

Another object is to provide a fuel pump with means associated with the intake and with a bypass return passage for eliminating hum.

Other objects will become readily apparent from the following detailed description taken in connection with the accompanying drawing, in which:

Fig. 1 is a longitudinal, vertical section through a preferred form of the invention.

Fig. 2 is a fragmentary view approximately along the line 2—2 of Fig. 1.

Fig. 3 is a fragmentary section in the same plane as Fig. 1 through a modified form of the invention.

Fig. 4 is a similar fragmentary view through still another form of the invention.

While I have illustrated in the drawing and shall hereafter describe in detail a preferred form of the invention, together with modifications thereof, it is to be understood that I do not intend to limit the invention to the particular forms and arrangements shown. The scope of the invention will be defined by the appended claims.

In the form selected for purposes of disclosure, the invention is embodied in a fuel pump of the type disclosed and claimed in Patent No. 2,232,983, dated February 25, 1941, which issued on applicant's copending application, Serial No. 212,475, filed June 8, 1938. As shown in Figs. 1 and 2, the fuel pump consists generally of a two-part casing 19, 20, a pumping device or mechanism 21, a drive shaft 22, a mechanical seal 23, for the drive

shaft, and a strainer 24. A control valve mechanism 25 forms no part of the present invention but together with other parts of the pump is claimed in said prior application. It is contemplated that the shaft 22 will be connected by suitable means to a driving motor (not shown), and that an inlet port 26 will be connected to a source of fuel supply such as a tank (not shown). The casing parts 19 and 20 are formed to provide a somewhat cylindrical chamber or recess 28 in which the pumping mechanism 21 and strainer 24 are positioned. The pumping mechanism generally consists of an externally toothed roller 30 secured to the shaft 22 by a pin 31, an internally toothed ring 32 having the lower portion thereof meshing with the roller 30 and an intermediate crescent guard 33. The complete details of this mechanism are disclosed in said copending application and function in a well known manner to draw fuel in through the inlet port 26, through the chamber 28 and in through an intake port 34 formed in an end plate 35 of the pumping mechanism. Upon rotation of the shaft 22 in a clockwise direction, as shown in Fig. 2, the fuel is carried in the cavities of the roller and ring past the crescent guide 33 and forced out through a discharge port 36. The strainer 24 is cup-shaped and surrounds the pumping mechanism so that all of the fuel entering the inlet port 26 must pass through the strainer to reach the intake port 34.

The fuel discharged through the port 36 is conducted to the valve mechanism 25 as shown more fully in said copending application, and from said valve mechanism passes either through an outlet port adapted for connection to the oil burner or through a bypass port 27 (Fig. 1).

At its upper end, the bypass port 27 extends up to the chamber 28 so that the bypassed oil flows through this chamber. A plug 27' is inserted in the lower end 27" of the bypass port 27.

In order to eliminate the hum which sometimes occurs during operation of the pumping mechanism, a closed air pocket is formed in a portion of the chamber 28. As illustrated in Fig. 1, such an air pocket 38 is formed in the casing part 20 by stretching a diaphragm 39 across the end of the chamber 28 and securing it in position by clamping it between the adjacent surfaces of the parts 19 and 20, these parts being secured together by means of a plurality of headed screw devices 40. The diaphragm 39 is preferably made of a fuel resistant material, such as an impregnated cloth generally referred to as "airplane" cloth. The left-hand or inner surface of this diaphragm forms one wall of the air pocket 38,

whereas the right-hand or outer surface of the diaphragm forms an end wall of the chamber 28, so as to be subjected to the fuel in said chamber.

The objectionable hum which occurs during the operation of a fuel pump is generally caused by the pulsations on the intake side of the pump. These pulsations are eliminated by the cushioning effect of the yieldable diaphragm which forms one wall of the closed air pocket.

In the form illustrated in Fig. 3, the casing part 20' has a recess 45 in its inner surface forming an air pocket or chamber. A diaphragm 38' closes the recess 45 and is secured in place on the casing part 20' by means of a suitable ring 46. In this form, the pumping mechanism 21 is located in a chamber 28' and a strainer 24' is positioned intermediate the inlet port 26 and the pumping mechanism. Here again, a closed air pocket is formed within the casing and has one wall thereof formed by a diaphragm of airplane cloth which is subjected to the fuel within the chamber 28'.

In the form illustrated in Fig. 4, the casing part 19 and the pumping mechanism are in the same form as shown in Figs. 1 to 3. A strainer 24" surrounding the pumping mechanism is doubled-back at the left-hand end to provide a space for an anti-hum device designated generally 50. This device consists of a ring 51 having diaphragms 52 and 53 stretched across the opposite ends thereof and clamped thereagainst by means of clamping rings 54 and 55 which are suitably secured to the ring 51. This anti-hum device may be supported on the strainer as shown in Fig. 4 instead of being fastened to the casing part 20, but preferably the ring 54 is secured in air-tight relation to the adjacent surface of the casing part 20", as by means of solder or suitable screw devices (not shown). Connecting ports 57 and 58 in the casing part 20" communicate with a port 59 in the casing part 19 which in turn connects with the bypass port 27 of the unit.

The invention provides a simple and inexpensive means for preventing hum during operation of the fuel unit. In the forms illustrated in Figs. 1 to 3, wherein the internal bypass is in use, the bypassed oil, as well as the incoming oil, passes through the chamber 28, one wall of which is formed by the diaphragm 38 of the closed air pocket. When the fuel unit is used in a circuit

having a return conduit to the tank, the form illustrated in Fig. 4 may be used. The return conduit is connected to the lower end 27" of the bypass port 27 and the upper end of the bypass port is closed by a plug 27a. In this event, the hum is eliminated from the return line as well as from the intake. In either event, a closed air pocket or chamber having a flexible wall subjected to the fuel serves to eliminate the hum.

10 The forms of the invention illustrated in Figs. 1 to 3 may readily be used in circuits having return lines by removing the plug 27' from the lower end of the bypass port 27 and inserting a plug 27a in the upper end thereof.

15 As illustrated herein, the flexible wall is formed by means of a diaphragm made of an impregnated linen cloth which is water-proof and oil-proof. It will be apparent that other flexible or yieldable materials may be utilized for forming the diaphragm provided they are resistant to the oil with which they come in contact.

20 I claim as my invention:

1. A fuel pumping device having, in combination, a casing having a recess provided with an inlet port, and means forming a portion of a return bypass port, pumping mechanism positioned in said recess, an outlet port in said casing through which the pumping mechanism discharges some of the pumped fuel into the bypass port, a cover for said recess secured to said casing, means positioned in said recess forming a closed air chamber having one flexible wall subjected to the fuel in said recess and another flexible wall sealed from the fuel in said recess, and means for establishing communication between said second flexible wall and said return bypass port.

2. In combination, a fuel pumping device having a casing provided with inlet, outlet, and return by-pass ports, pressure operated valve means controlling said outlet and by-pass ports, pumping mechanism in said casing adapted to draw fuel through the inlet port and force it out the outlet and return ports, and means forming a closed air chamber having flexible walls subjected independently to the fuel passing through the inlet port and the fuel passing through the return port.

GUNNAR A. WAHLMARK.
